UNITED STATES PATENT OFFICE.

ELIOT KEEN, OF NEW YORK, N. Y., ASSIGNOR TO TELEGRAVURE COMPANY, A
CORPORATION OF NEW YORK.

TELEGRAPHY.

1,176,148.

Specification of Letters Patent. Patented Mar. 21, 1916.

Application filed March 8, 1910. Serial No. 548,047.

To all whom it may concern:

Be it known that I, ELIOT KEEN, a citizen of the United States, residing in the borough of Manhattan, in the city, county, and State 5 of New York, have invented certain new and useful Improvements in Telegraphy, of which the following is a specification.

My invention relates to improvements in the art of telegraphy and more particularly 10 to a certain novel method and to apparatus for performing the same especially adapted to the transmission and reproduction of pictures. Certain features of my invention are, however, of more general application.

15 In the attempts which have heretofore been made in the direction of transmitting pictures, many difficulties have been met with which have appeared insurmountable, among the chief of which may be mentioned 20 the difficulty of securing that degree of synchronism between the sending and receiving machines required by all processes of which I am aware, previous to mine; the necessity for the most accurate construction 25 and delicate adjustment in all forms of apparatus as previously constructed; the impracticability of operating the mechanism at any efficient speed, or of transmitting pictures through repeaters or the other 30 standard apparatus found in existing telegraphic circuits; or in any apparatus in which a make and break circuit is used, successive impulses being designed to reproduce successive parts of the picture, the inability 35 to transform the impulses into a record corresponding with a satisfactory degree of accuracy to the original picture. I overcome all of the foregoing difficulties, and also many others which have been heretofore 40 found to preclude the practical operation of devices of this character in a manner which will be clear on perusal of the following specification.

In the accompanying drawings, which 45 form a part of this specification, I have chosen to show for purposes of illustration certain forms of my improved mechanism, which illustrate what I now consider the preferred embodiment thereof, but I do not 50 wish to be limited thereto, as my improvements in process may be carried out by many other forms of apparatus, and my apparatus is capable of wide modification.

In these drawings Figure 1 is a plan 55 view of my preferred form of transmitting

apparatus; Fig. 2 is a transverse section of the same taken on line II—II of Fig. 1; Figs. 3 and 4 are, respectively, detail sectional views taken on lines III—III and IV—IV of Fig. 1; Fig. 5 is an end elevation 60 and Fig. 6 a side elevation of my receiving apparatus; Fig. 7 is a detail view of the sprocket and ratchet wheels used for driving the receiving machine at half speed; Fig. 8 is a plan view of a portion of the receiving apparatus showing the movable armature and the means for operating the same; Fig. 9 is a detail sectional view of a portion of the armature moving mechanism; Fig. 10 is a detail plan view of the armature 70 stop and fixed contact; Fig. 11 is a perspective view of the record-film-box; Fig. 12 is a detail view of a portion of the same, parts being broken away; Fig. 13 is an elevation of parts of my receiving machine looking at 75 the same from the opposite side to that illustrated in Fig. 6; and showing the means for rotating the film carrying drum and for moving the same and its containing box longitudinally; Fig. 14 is a view partly in 80 transverse section of the diaphragm box and film box; Fig. 15 is a sectional plan view of the diaphragm box; Fig. 16 is a detailed view of one form of aperture forming diaphragms which I may use in my receiving machine; Fig. 17 is a diagrammatic view illustrating 85 the location of these diaphragms and the path of a light beam controlled by them and directed upon the record film; Fig. 18 is a rear elevation illustrating in detail a different form of aperture forming device, this being the form shown in Figs. 14 and 15; Fig. 19 is a detailed elevation of a delayed 90 circuit closer; Figs. 20, 21 and 22 are detail views illustrating the positively driven switch controlling the end of the line synchronizing mechanism; Fig. 23 is a diagram 95 of the circuits of the receiving machine; Fig. 24 is a detail view of a light controlling 100 diaphragm forming a part of a modified form of record making apparatus; Figs. 25 and 26 are views in front elevation and sectional plan, respectively, illustrating the modified form of diaphragm box and drop shutter, the diaphragm box containing the 105 diaphragm shown in Fig. 24; Fig. 27 is a diagrammatic view illustrating the path of the light beam through the diaphragm box shown in Figs. 25 and 26; Fig. 28 is a detail view of a pair of aperture forming and 110

locating diaphragms used in connection with the diaphragm shown in Fig. 24.

Referring to the drawings in detail, and particularly to the transmitting mechanism illustrated in Figs. 1 to 4, the numeral 1 designates a base plate, upon which are mounted frames 2 and 3, carrying suitable bearings in which are journaled shafts 4, 5, 6, and 7. Shafts 5 and 6 are preferably provided with longitudinal key-ways 8 and 10, provided with feathers 11, sliding in the key-ways. These pulleys are mounted in a guide frame comprising the side bars 12 and 13, connected at their ends to the split nuts 14 and 15, which engage with the screw shafts 4 and 7. The split nuts are formed of two halves pivoted on pins 16, screws 17 being provided to open and close these split nuts, thus causing them to engage or disengage the screw shafts. Carried by the pulleys 9 and 10 is the band 18, preferably of thin metal, and provided with a plurality of contact points or brushes 19, which pass over the surface of the plate 20. The plate 20, or sending plate, is prepared in such manner that it presents a number of conducting and non-conducting portions, or raised and depressed portions, corresponding to the picture or message to be sent. This plate 20 usually takes the form of a half-tone prepared by the well-known process of photographing a picture through a half-tone screen, and either etched or similarly having the half-tone impression photographed thereon in some suitable form of enamel or non-conducting chemical preparation. As indicated, the half-tone comprises a number of dots 21, of different sizes, on a blank background. The picture may be either a positive or negative, that is, the dots may be conducting spaces and the background non-conducting space, or vice versa. In the further description of this apparatus I will treat the dots as being conducting spaces. Means are provided for insulating the plate 20 from the rest of the apparatus, these means preferably taking the form of a carriage of insulating material to which the plate is secured. The carriage is movably mounted upon the base 1 and is held between springs 22 and thumb screws 23 in order to permit it and the plate 20 to be adjusted to bring the centers of the rows of dots on the latter beneath the points or brushes 19. A pair of flat springs 24 or equivalent means may be provided to press against the band 18 to regulate the tension of the latter and prevent the same from becoming slack.

For rotating the shafts 5 and 6, and with them the pulleys 9 and 10, thus causing the band 18 to move, and the points 19 to traverse the plate 20, I provide the shafts 5 and 6 with a worm gear 25, these worm gears being engaged, respectively, by two worms

26 and 27 carried on the ends of a shaft 28. Shaft 28 is driven through suitable gearing 29 from the clutch shaft 30, which carries the clutch members 31 and 32, the former being slidably mounted upon the shaft, but held from rotation thereupon by means of a key 33, sliding in a key-way 34. The clutch member 32 is free to rotate upon the shaft and has connected to it the gear 35 receiving power from the driving pinion 36 mounted upon the shaft 37, which may be the armature shaft of an electric motor, or any other suitably driven shaft. The clutch member 31 is normally held in engagement with the clutch member 32 by means of a spring 38 mounted upon the shaft 30 and abutting against a collar 39 fixed thereto.

40 is an electro-magnet, which when energized serves to draw the clutch member 31 out of engagement with the clutch member 32, thus permitting the latter to revolve freely on the shaft 30, which remains stationary. The screw shafts 4 and 7 are preferably rotated from shafts 5 and 6, through gears 41 secured to the latter, which engage gears 42 carried by sleeves 43 rotatably mounted upon the end portions of shafts 4 and 7, these sleeves having fixed thereto collars 44 to which are pivoted pawls 45. The latter engage ratchet wheels 46, fixed to the screw shafts 4 and 7. Through this mechanism the rotation of the shafts 5 and 6 will cause the rotation of the screw shafts 4 and 7, but because of the ratchet connections above described, the latter shafts may be rotated by hand independently of the shafts 5 and 6, to permit an adjustment of the guide frame 12-13 and the pulleys 9 and 10. The points or brushes 19 may thus be brought into proper position for starting the sending operation.

In order to transmit an electrical make and break impulse by means of this apparatus, the wire 47 of an electric circuit is connected to some part of the apparatus which is in electrical connection with the points or brushes 19, as, for instance, to the binding post 48 secured to the frame member 3. The other circuit wire 49 is connected to the plate 20, as by means of the binding post 50. As the plate 20 is insulated from the frame members 2 and 3, and the parts carried thereby, the circuit is closed only when one of the brushes 19 is in engagement with one of the conducting dots 21. The wire 47 leads to a relay 51 which is connected by wire 52 with a relay 53, a wire 54 leading from the latter to one side of the battery 55, to the other side of which is connected the wire 49. 56 and 57 are the main line wires, wire 56 being connected to the armature 58 of the relay 51. A wire 59 connects the contact of this relay with the magnet of relay 60, to which the other main line wire 57 leads. A wire 61 connects the arma-

ture 62 of the relay 60 with the clutch magnet 40, the circuit through the latter being completed through wire 63, battery 64, wire 65, armature 66 of relay 53, and wire 67 connecting the contact of relay 53 with the back contact 68 of relay 60. It will thus be seen that when one of the brushes 19 reaches one of the conducting dots 21, the circuit will be closed through the brush 19, band 18, pulleys 9 and 10, shafts 5 and 6, frame 3, wire 47, relay 51, wire 52, relay 53, wire 54, battery 55 and wire 49 back to the plate 20. Relays 51 and 53 will thus be energized, the former acting to draw over the armature 58, thus closing the main line circuit through wire 56, armature 58, wire 59, relay 60, wire 57, and suitable apparatus at the other end of the line to be hereinafter described. The closing of the two circuits as above described, while energizing relay 53 with the result of connecting wires 65 and 67 through the armature 66 of relay 53, also energizes relay 60, thus breaking the circuit between wire 67 and wire 61 by the action of relay 60 in drawing its armature 62 away from the back contact 68. The circuit through the clutch magnet 40 thus remains broken, the clutch remains operative, and power is transmitted to the sending mechanism. If, however, one of the brushes 19 is in contact with one of the dots 21, and the main line circuit 56, 58, 59, 60, 57 is broken at the receiving station, or at any point in the line, relay 60 will cease to be operative, and the armature 62 will be drawn back by its spring against the back contact 68. The circuit will thus be closed through 62, 68, 67, 66, 65, 63, clutch magnet 40 and wire 61. Clutch member 31 will now be drawn back out of contact with clutch member 32, and the latter, with gear 35, will revolve freely, thus permitting the sending apparatus to stop.

Referring now to the receiving mechanism, the latter preferably comprises in general terms a sensitized film and means for exposing successive portions of the same to a beam of light having a size, intensity or duration proportioned to the impulse sent over the main line wires by the sending apparatus. As will be apparent, however, other than photographic recording means may be used for carrying out my invention under some circumstances. A preferred form of my receiving apparatus is constructed as follows: 69 is an electric motor, or other suitable source of power, which drives through a chain 70, a sprocket 71 fixed to a clutch member 72, the sprocket 71 and clutch member being rotatably mounted upon a shaft 73. The latter is journaled in suitable bearings in the main frame 74 of the receiving apparatus and has splined upon it a clutch member 75 adapted to be normally held in engagement with the clutch

member 72 by a spring 76. An electromagnet 77 serves, when the circuit is completed through it in a manner to be herein-after described, to draw the clutch member 75 out of engagement with the member 72, thus permitting the latter and the sprocket 71 to revolve freely. The shaft of the motor 69 also carries a sprocket 78 which drives through a chain 79 a sprocket 80 mounted on the shaft 73. The sprocket 80 is arranged to drive the shaft when rotated in one direction, for this purpose having pivoted to it a pawl 81 held in engagement by means of a spring 82, with a ratchet wheel 83 fixed to the shaft. When the shaft is rotating faster than the sprocket, however, the pawl on the latter will simply snap over the teeth on the ratchet wheel. The latter condition arises whenever the circuit through clutch magnet 77 is broken, thus permitting shaft 73 to be driven through chain 70 and clutch gear 71, as the sprockets are so proportioned that the speed of shaft 73 when driven through chain 70 will be twice what it is when driven through chain 79. It will thus be seen that the effect of closing the circuit through clutch magnets 77 will be to substitute for one driving means another acting to drive the apparatus at half speed.

Upon the shaft 73 is mounted a worm 89, which meshes with a worm gear 90, splined to the shaft 91. The latter is slidably and rotatably supported in suitable bearings, and preferably has one end squared as indicated at 92. 93 is a drum adapted to carry upon its surface a sensitized film 94, some means, such as a key 95 entering a slot in the drum, being provided to secure the film to the drum. In order to avoid the necessity for mounting the entire receiving apparatus in a dark room, the drum 93 is supported in a light proof box 96, the drum being provided with hubs 97, which project through the end walls of the box and are rotatably mounted therein. The hubs 97 are preferably provided with square sockets 98, one of which is adapted to receive the square head 92 of the shaft 91, a set screw 99 being provided to hold the end of the shaft in the socket. Rotation is thus transmitted from the gear 90 to the drum 93. The socket 98 at the other end of the drum receives the squared end 100 of a screw shaft 101, the latter passing through a threaded opening in the fixed nut or bracket 102. The box is preferably provided on its under surface with bearing blocks 103 adapted to slide upon longitudinal guide bars 104. As will be apparent, the shaft 101 is rotated with the drum 93, and through its engagement with the bracket 102 moves the drum 93 and the box 96 in which it is mounted, longitudinally. The box is provided with a hori-

zontal slit 105, which registers with an opening 106 in the rear wall 107 of the diaphragm box to be hereafter described. The box 96 slides in close contact with this wall 107, any suitable means being provided for insuring the exclusion of light from the cracks between the box and the wall. This may advantageously be done by covering either the side of the wall as indicated at 108, or the side of the box, or both, with a layer of velvet or like material. For closing the slit 105 when the box is removed from contact with the wall, I provide a shutter device such as that shown in Figs. 12 and 14, which comprises a flap 109 hinged to the inside of the box, and adapted to fall by gravity, or be held by the pressure of a spring over the opening. A lever 110 may be provided for lifting this flap, the shaft of the lever passing through a bearing box 111 in the end of the camera box and having an operating handle 112.

For controlling the admission of the beam of light through the opening 106 and the slit 105 to the interior of the camera box to act upon the sensitized film 94, I provide certain mechanism which I will now describe: Upon the main frame adjacent to the camera box I secure a box 113 having an opening 114 in its front wall in line with the opening 106 in its rear wall. The opening 114 is controlled by shutter 115 mounted upon the vertically movable standard 116, to the lower end of which is secured the armature 117 of the electro-magnet 118. The armature 117 is preferably so disposed that it tends to drop away from the magnet 118 by gravity, but in order to insure operation of the shutter and increase its speed, I preferably place above it a compression spring 119. In order to raise the shutter 115 and expose the opening 114, and to bring the armature 117 into the field of magnet 118 at stated intervals, I journal in the diaphragm box 113 a shaft 360 having mounted thereon a cam 120 adapted to engage an arm 121 projecting from the standard. This cam has a portion of increased radius 122 which acts when the cam is rotated to raise the armature and open the shutter, and has an abrupt offset at 123, so that when rotated it permits the shutter to instantly close under the action of gravity and of the spring 119, unless at the time this offset is reached the magnet 118 is energized.

The shaft 360 is driven from the main driving shaft 73 through gearing 125 and the shaft 126, which carries bevel gear 127 engaging with a bevel gear 128 fixed to the shaft 360. The latter shaft is provided with a spur gear 361 which engages with a spur gear 362 on a shaft 124. The gear 129 on shaft 124 engages with the gear 130

upon the shaft 131, the gear 130 also meshing with the gear 132 fixed to the shaft 133. The shafts 124, 131 and 133 carry the light controlling diaphragms which form an important feature of my invention.

70

The light controlling or aperture-forming diaphragms are shown in transverse section and plan in Figs. 14 and 15, respectively, and are shown in rear elevation on an enlarged scale in Fig. 18. They comprise a pair of eccentric disks 134 secured to shafts 124 and 133, and a disk 135 having twice the eccentricity of the disks 134 and mounted on shaft 131. The disks need not be complete eccentrics as but about one-half of the edge of each disk is actually used in forming the light aperture 136 and their active edges should, to be theoretically exact, be arcs of Archimedean spirals rather than circular arcs. In practice, however, I find that satisfactory results are obtained by making the disks circular and giving them a slight eccentricity. These three disks form three sides of the aperture 136, the fourth side being formed by the stationary 90 diaphragm 137. In Fig. 18 the aperture 136 is shown at its maximum size, it being understood that when the disks are rotated so that their points of greatest radius are adjacent, the aperture 136 will either be reduced to a very small area or closed entirely. One of the disks, preferably the disk 135, is provided with an extension 138 forming a shutter which acts immediately after the maximum size of aperture has been 100 reached to close the aperture entirely until it has reached its minimum; the aperture is then uncovered again and slowly grows until the maximum is again reached. In order to prevent diffusion of the light through the 105 aperture 136, I preferably mount adjacent to the same a piece of ground glass, or similar translucent material 139, this material being preferably secured to the stationary diaphragm 137 as shown. The diaphragms 110 serve to expose a larger or smaller surface of this illuminated screen, the image of which is photographed upon the sensitized film 94. A suitable lens 140 is provided for focusing the illuminated square upon the 115 film, in order to give a sharp outline thereto. The disk 135 is given twice the eccentricity of the disks 134, and the fourth side of the aperture 136 is formed by the stationary diaphragm 137 in order to compensate 120 for the continuous movement of the film carried on drum 93. Owing to this movement the film uncovers itself beyond the edge of the diaphragm 137 at the same rate that the exposed portion of the film grows 125 laterally, the effective opening of the diaphragm 135 being decreased to a like amount. The effect is thus produced of an aperture opening equally in all directions, and the resultant exposed portion or dot 130

80

grows from a fixed center equally on all sides.

In order to maintain a positive relation between the moving diaphragm, the shutter opening cam and the drum 93, these parts are all geared together and driven from a common driving shaft, as already described. The result is to insure the making of the several exposures upon the recording film at equally spaced intervals, that is, the centers of successive exposed portions or dots are equally spaced. From the nature of half-tone plates it will be understood that the sending half-tone shown in Fig. 1 is composed of parallel rows of dots, the dots in adjacent rows being staggered, so that the rows do not begin at equal distances from the edge of the plate; moreover, every alternate row will have one dot less than the preceding row. In order to produce a similar arrangement of dots on the record film, it is necessary to so proportion the gearing between the drum 93 and the diaphragm and shutter mechanism that the latter will go through a number of cycles equal to the mean number of dots per row for every revolution of the drum, that is to say: For the first revolution of the drum, supposing the number of dots in the first row of the sending half-tone to be 100, the diaphragm and shutter mechanism will go through $99\frac{1}{2}$ cycles. During the second revolution of the drum the shutter mechanism will again go through $99\frac{1}{2}$ cycles, although the number of dots in the second row is only 99. This result may be readily accomplished by properly proportioning the drum driving gear 90 and its driving worm 89. For example, if the number of dots in the long row of the half-tone is 100, the gear 90 should have 199 teeth, the worm 89 being given a double thread.

The movable diaphragms and their driving mechanism as above described serve to locate the exposed portions or dots upon the film, with their centers arranged in the same relation as in the sending half-tone, and also serve in combination with the drop shutter 115 to determine the size of the exposed portions. This size is fixed by the period after the commencement of the opening of the aperture 136, at which the drop shutter falls, as the exposed portion upon the film grows continuously owing to the enlargement of the aperture 136 until the light is cut off by the drop shutter.

In order to maintain the cycles of the sending and receiving machines in such relation to each other that the exposures of the receiving film may be made at proper times to correspond with the impulses being transmitted by the sending machine so that the drop shutter will be operated at proper intervals, the sending and receiving machines may be operated in synchronism. In

this case it will be necessary to so drive the machines that a brush 19 reaches and passes over the center of each successive dot at the same instant that the diaphragms commence the formation of the aperture 136. To maintain the machines in synchronism, however, is a matter somewhat difficult of accomplishment, and I have devised means by which this may be avoided, which I regard as an important feature of my invention. I accomplish this result by in effect sending each dot as a separate operation and recording the same before beginning the transmission of the next dot.

The mechanism by which I send and receive the single impulses and control the relative operation of the two machines is as follows: Referring to the diagram of the electrical circuits at the receiving end of my apparatus, Fig. 23, it will be seen that the main circuit wire 56 connects with the relay 141, which is connected by the wire 142 to the back contact 143 of the relay 144. The armature 145 of this relay is connected by a wire 146 to the back contact 147 of a relay 148, the armature 149 of which is connected to the main line wire 57. It will thus be seen that the main line circuit passes through the relay 141 and is closed only when the circuits of relays 144 and 148 are open. The relay 141, I call the main line relay, and when energized it acts to close what I call the primary circuit. This circuit starts from the main line relay contact 150, from which wire 151 leads to the primary magnet 152, wire 153 leading from the latter to the first primary relay 154. The circuit then continues successively through wire 155, second primary relay 156, wire 157, third primary relay 158, wire 159, fourth primary relay 160, wire 161, fifth primary relay 162, wire 163, battery 164, wire 165, wire 166, through the shutter magnet 118 and wires 167 and 168 back to the armature 169 of the main line relay 141. It will thus be seen that whenever the main line relay 141 is energized, the primary magnet 152 will be energized, the shutter magnet 118 will be energized, holding the shutter open if its armature has been moved into proximity therewith by the cam 120, and the several primary relays 154, 156, 158, 160 and 162 will be energized. The main line relay 141 will be closed whenever the main circuit is closed, unless the circuits of either relays 144 or 148 are closed. The purposes of these two relays and their modes of operation will be fully described hereinafter.

The primary magnet 152 and its driving mechanism is more fully shown in Figs. 5, 6, 8 and 9. From these figures, and particularly Fig. 8, it will be seen that the primary magnet 152 is carried by a cross head 170, slidably mounted upon guides 171 supported on the main frame 74 of the re-

ceiving apparatus. The cross head 170 carrying with it the primary magnet 152 is reciprocated by means of a pitman 172 connected to a crank 173 mounted upon the end 5 of the vertical shaft 174. This shaft carries a gear 175 which meshes with a gear 176 fixed to a shaft 177, which is driven through suitable gearing 178 from the main driving shaft 73. The shaft 174 has fixed to it a 10 cam 179 which engages the contacts 180, holding the same closed during substantially a half revolution of the cam shaft. The cam is so placed as to be out of engagement with the contacts 180 during the movement of the 15 primary magnet 152 in the direction indicated by the arrow, which I call the forward stroke of the magnet, the contacts being closed during the movement of the magnet in the opposite direction. I also provide 20 a secondary magnet 181, which is mounted upon a cross head 182, slidably mounted upon guides 183. A pitman 184, connected to a crank 185 fixed to the end of the shaft 186, serves to reciprocate the secondary magnet 181, the shaft 186 being driven through a gear 187 from the gear 176 above described. The shaft 186 has secured to it a 25 cam 188, similar to the cam 179 on the shaft 174, and engaging with a pair of contacts 189. The cam 188 closes the contacts 189 during substantially the same period that the contacts 180 are closed, though it may be advantageously arranged to permit the contacts 189 to open slightly before the contacts 180 are open. It is to be noted that the 30 crank 185 is twice the length of the crank 173, whereby the secondary magnet 181 has twice the throw of the primary magnet 152, and therefore moves at twice the velocity 35 of the latter. The circuits to the magnets 152 and 181 may be made through the guides 171 and 183, respectively, as shown, or in any other suitable manner. Slidably mounted between these two magnets in a channel 40 190 secured to the main frame 74, is a floating armature or movable contact member 191 adapted to be attracted by either of the magnets 152 or 181, whichever happens to be energized at a particular time, and to be 45 moved in the direction in which the magnet by which it is at the time attracted is moving. It will be seen that whenever the armature is attracted by the magnet 152, it will move at one-half the speed of that at which 50 it would move if attracted at a corresponding time by the magnet 181. Wire 192 makes a permanent contact with the armature 191 and at one end of the channel 190 is a contact 193 with which the armature engages 55 at the beginning and end of its travel. Fig. 10 shows this contact and one end of the floating armature or movable contact in detail.

350 is a stop for limiting the movement 60 of the armature, being preferably made ad-

justable in order to locate the end of the armature 191 properly between the contacts, and to provide for taking up wear.

Considering now the operation of the parts just described, supposing the parts to be in the position illustrated in the diagram Fig. 23, the primary magnet 152 moving in the direction indicated by the arrow, or in a forward direction, and the main circuit to be closed by the first brush 19 coming in 75 contact with the edge of one of the conducting dots 21, the relay 141 will be energized, closing the primary circuit through the primary magnet 152, the shutter magnet 118 and primary relays 154, 156, 158, 80 160, 162.

In the normal condition of affairs, the circuits through the relays 144 and 148 will be broken. The magnet 152 being now energized, will move the armature 191 in the 85 direction of the arrow, thus breaking the contact between the same and the contact 193, as indicated. The circuit which includes the contact 193 comprises wire 194, battery 195, wire 196, relay 197, wire 198, relay 199, wire 200, relay 201, wire 192, and the floating armature 191; thus the breaking of this circuit causes the de-energizing of relays 197, 199 and 201. The de-energizing of relay 201 permits its armature 202 90 to be drawn against its back contact 203, which closes a circuit through wire 204 and battery 205, wire 206, wire 167, the shutter magnets 118, wire 166 and wire 207, thus energizing the shutter magnets and causing them to remain energized as long as the circuit through relay 201 is broken.

The de-energizing of relay 199 permits its armature 208 to contact with its back contact 209, thus closing the circuit through wire 210, armature 211 and back contact 212 of relay 162, wire 213, battery 214, wire 215, armature 216 and contact 217 of relay 218, wire 219, secondary magnet 181, and wire 220, provided relay 162 is de-energized and the circuit through relay 218 is closed. Relay 162, which is one of the primary relays above described, is closed only when the main line is closed, that is, when an impulse is coming over the same from the sending machine; consequently the circuit last described which passes through the secondary magnet, and which I accordingly call the secondary circuit, can only be closed when no impulse is coming over the line. The circuit from relay 218 is made through wire 221 to one member of the cam operated contact 180; thence from the other member of this contact through wire 222, relay 223, wire 224, battery 225 and wire 226, so that relay 218 is energized only when cam 179 is acting to close the contact 180, which, as has been above described, takes place during the back stroke or half-revolution during which the primary and secondary mag-

nets are moving towards the contact 193. It will accordingly be seen that the secondary magnet can operate to move the armature 191 only in the direction of contact 193 and only when there is no impulse coming over the main line.

The third relay 197 in the floating armature circuit acts to draw its armature 227 into engagement with contact 228, which 5 closes a circuit through wire 229, contact 230 and armature 231 of relay 232, wire 233, contact 234 and armature 235 of primary relay 160, wire 236, relay 237, wire 238, battery 239 and wire 240, provided relays 232 and 160 are energized. The latter being 10 one of the primary relays, is energized whenever an impulse is coming over the main line, while the relay 232 is contained in the circuit comprising wire 241, contact 189, wire 242, battery 243 and wire 244. Contact 189 is closed by cam 188 from the 15 beginning of the back stroke, that is, from the point when the primary and secondary magnets are farthest from the contact 193, until they approach almost if not entirely to the limit of their travel adjacent to contact 193. The relay 237 acts when energized to draw its armature 247 against its contact 248, thus closing a circuit through 20 wire 249, clutch-magnets 77, wire 250 and battery 251, thus energizing the clutch magnets, drawing the clutch member 75 out of engagement with member 72 and permitting the machine to be dropped to half 25 speed. The conditions necessary then to dropping the machine to half speed are seen to be (1) that the primary and secondary magnets are on their back stroke, (2) that the armature 191 is in engagement 30 with the contact 193, and (3) that there is an impulse coming over the main line.

The relay 223 acts when energized to draw its armature 252 against its contact 253, thus closing a circuit through wire 254, relay 148, wire 255, battery 256, wire 257, back contact 258, and armature 259 of relay 156, wire 260, contact 261, carried by a bar 262 of the double switch 263 to be hereafter described, fixed contact 264 of the double 55 switch, and wire 265, provided relay 156 is deenergized, which, as this is one of the primary relays, will be whenever there is no impulse coming over the line, and provided the double switch is in the position shown in the diagram, which is its normal condition throughout the sending of a row of dots, its condition being only changed at or near the end of a row of dots. Relay 223 being in the circuit controlled by contact 180 60 and cam 179, as above described, is energized only during the back stroke of the primary and secondary magnets. It will thus be seen that an impulse on the main line having terminated, thus deenergizing relay 156 and permitting its armature 259 to engage its

contact 258, the primary and secondary magnets being on their back stroke, the circuit through relay 148 will be closed, thus breaking the main line, so long as the primary and secondary magnets are completing the 70 back stroke which, at the time, they are on. The breaking of the main line stops the sending machine, as has been above described, so that an impulse cannot be sent until the primary and secondary magnets 75 start again on their forward stroke. The completion of the record of one impulse is thus insured before the coming of another.

The apparatus as thus far described comprises the means for sending and recording 80 dots throughout each row of dots.

Considering the operation briefly, if now it be imagined that a small dot is to be transmitted and recorded, the impulse may reach the receiving machine at any time after the 85 primary and secondary magnets start on their out-stroke, that is, in the direction indicated by the arrow. It may be that the impulse will be received soon after the primary magnet starts, say for purposes of 90 illustration, when the primary magnet has made one-sixth of its outward journey, and lasts until perhaps two-thirds of the outward travel of the primary magnet has occurred. In that case the primary magnet will seize 95 the armature 191 and move it away from contact 193 for a distance equal to one-half of its full travel. Although the impulse has now ceased, the mechanism of the receiving machine continues to be driven by the motor 100 69 and the primary and secondary magnets continue on their outward travel, without, however, moving the armature, until they reach the end of the out-stroke. At this time the cam 120 will have raised the 105 shutter to open position where it will be held by the magnet 118, the circuit through which is closed by the deenergizing of relay 201, in the manner already described. At this time the movable diaphragms 134 110 and 135 will be in position to commence the formation of an aperture 136, and cams 179 and 188 will close contacts 180 and 189, respectively. The continued operation of the diaphragms 134 and 135 will cause the aperture 136 to slowly increase in size, while at the same time the primary and secondary magnets will start on their back stroke. Relay 218 being now energized by the closing of contact 180 and the main line being 115 broken, the secondary circuit will be closed, thus energizing the secondary magnet 181 and causing the same to seize the armature 191 and move the same toward the contact 193. This continues until the armature engages the contact, when the circuit is closed through relays 201 and 199. The energizing of the former breaks the circuit through the shutter magnet, permitting the shutter to close, while the energizing of the latter 120

breaks the circuit through the secondary magnet, thus permitting it to release the armature in engagement with the contact 193.

- The dropping of the shutter 115 determines the exposure which has been taking place through the constantly growing aperture 136, and therefore fixes the size of the exposed portion or dot upon the recording film. The area of this dot is thus a function of the length of impulse, being dependent upon the time taken by the armature 191 to move from the position at which it was at the beginning of the back stroke, when the aperture 136 began to grow from a zero value, until the armature engaged the contact 193, this time interval depending upon the distance to which the armature was moved by the primary magnet during its out-stroke, which in turn is dependent upon the length of the impulse coming over the main line.
- As I do not aim to secure and do not require synchronism between the sending and receiving machines, other conditions than that just described may arise, for example: it is possible that an impulse of the length above referred to may arrive at a later period in the operation of the receiving machine; for instance—when the primary and secondary magnets have completed a large part, say three-quarters, of their out-stroke. In that case the primary magnet will be energized, seizing the armature 191 and moving the same for a small distance away from the contact 193. At the beginning of the return stroke the shutter will have been opened and the diaphragms will form the minimum aperture 136, as above described, thus beginning the exposure. The impulse being still on the main line, the primary circuit will remain closed, and as it passes through the shutter magnet 118 will maintain the same energized and the shutter open. The secondary magnet 181 will remain deenergized at this time for the reason that the circuit through it cannot be closed while the primary circuit is closed. This is the case for the reason that the circuit through the secondary magnet includes the armature 211 of one of the primary relays 162, so that when the primary circuit is closed and the relay 162 energized, the armature 211 will be withdrawn from its contact 212 and the circuit through the secondary magnet 181 broken at that point. The primary magnet will also remain energized and thus drag the armature 191 back toward the contact 193, the engagement with which, if the same is reached at the same instant that the impulse over the main line ceases, will permit the shutter to drop, making an exposure of perfect size. It will be seen that under these conditions the armature 191 will be moved out by the primary magnet during one-half of the im-

pulse and back during the other half of the impulse, whereas, under the condition above described, the primary magnet will move the armature out during the entire impulse, thereby taking the armature twice the distance away from the contact 193. The length of the exposure, which, however, depends upon the time which it takes to move the armature from its out position into engagement with the contact 193, will be the same in each case, for, although in the first case it must be moved twice the distance, it will be carried by the secondary magnet which moves at twice the speed of the primary magnet.

Another condition which may arise is that the primary magnet may take the armature out a certain distance and but a part of the way back before the impulse ceases. In that case the primary circuit will break, deenergizing the primary magnet, but the shutter magnet 118 will remain energized by means of the local circuit closed through armature 202 and back contact 203 of relay 201, which is deenergized. The breaking of the primary circuit deenergizes relay 162 and permits its armature 211 to engage its back contact 212, thus closing the secondary circuit, the cam 179 having already closed contact 180 and consequently energized relay 218. The secondary magnet is thus energized and picks up the armature 191, carrying it the remaining distance to the contact 193 at double the speed at which it was previously moved, the exposure being terminated as before, when the armature reaches the contact. The time taken to return the armature from its out-most position to the contact 193, first under the influence of the primary magnet, and then under the influence of the secondary magnet, will be just sufficient to produce the desired exposure. This will be seen when it is considered that the maximum length of dot on the sending plate will produce an almost continuous impulse on the main line—that is, the impulse will come at practically the beginning of the cycle of the receiving machine and continue practically to the end of it. As has been explained, however, the diaphragms increase the size of aperture 136 from zero to maximum during the second half of the cycle only; that is, while the primary and secondary magnets are on their back stroke. The maximum impulse is thus recorded in half the time required to transmit the same over the main line, and the same ratio holds true for impulses of less length. The movement of the armature 191 from its extreme outer position into engagement with contact 193, under the influence of the slow moving primary magnet, will thus record a dot of maximum area.

Taking now for purposes of illustration

a dot of one-half maximum area, it will be seen that the latter may be produced in any of the following ways:

First, the primary magnet may seize the 5 armature at the beginning of its out-stroke and move the same through its entire out-stroke, thus carrying the armature to its extreme position. The armature at the beginning of the return stroke will then be seized 10 by the secondary magnet which will return the armature to the contact in one-half the time taken to carry it out, thus producing one-half of the maximum exposure.

Second, the impulse may arrive after the 15 primary magnet has made a portion of its out-stroke, for example, one-half, in which case the armature will be carried only one-half of its extreme distance from the contact 193. The impulse, however, has been 20 only one-half received over the main line, so that it will continue during the first half of the back stroke of the primary and secondary magnets. The primary magnet will thus remain energized, the circuit to the 25 secondary magnet being broken so that the primary magnet will move the armature back, the impulse ceasing as the primary magnet causes the armature to engage the contact. The time taken by the primary 30 magnet to move the armature through one-half its maximum travel is the same as the time taken by the secondary magnet to move the armature through its entire travel, so that the exposure is in both cases the same.

35 In the third case the impulse may arrive when the primary magnet has made somewhat less than one-half of its outward travel—for example—one-quarter, in which case the primary magnet will move the 40 armature out three-quarters of its maximum distance. The impulse being now but three-quarters expended, the primary magnet will remain energized, moving the armature back one-quarter of its maximum travel at 45 the slow speed, which is sufficient to give an exposure one-quarter of the maximum. The impulse now ceasing, and the armature being still away one-half of its travel from the contact 193, the secondary magnet will be- 50 come energized, and, seizing the armature, will return it to its initial position. The movement of the armature through one-half of its maximum travel, under the influence of the secondary magnet, occupies sufficient 55 time to produce one-quarter of a maximum exposure, so that the two movements imparted to the armature,—first, by the primary magnet, and then by the secondary magnet, together occupy a time sufficient to 60 produce one-half of the maximum exposure, which is the result desired.

One other contingency may arise in the operation of my device: to wit, when an impulse arrives late, that is, when the sending machine is behind or running slower

than the receiving machine. Suppose, for instance, an impulse arrives just before the primary and secondary magnets have reached their extreme outer positions, in which case the primary magnet will have an 70 opportunity to move the armature 191 but a very short distance away from contact 193, the impulse continuing after the primary and secondary magnets start on their return stroke. In that case the primary magnet 75 continues to carry the armature and the primary circuit to energize the shutter magnet 118. The armature 191 having been carried but a very short distance away from the contact 193 is soon brought back into 80 engagement therewith, but the exposure is not terminated as the primary circuit is sufficient to hold the shutter open. The exposure will accordingly last until the impulse is terminated. Considering a concrete 85 illustration, an impulse of one-half the maximum length arrives when the primary magnet has moved through three-quarters of its outward travel. In that case the armature 191 will be moved by the primary 90 magnet one-quarter of its maximum distance from the contact 193, during the first one-quarter of the impulse, when it will start on its return travel, being moved by the primary magnet back into engagement with the 95 contact 193 during the second quarter of the impulse.

It will now be seen that but half of the time of the impulse has been expended, while the diaphragms have been opened for 100 a time sufficient to form one-quarter of a maximum aperture, or one-half of the desired aperture. As has been already explained, however, the diaphragms act to open an aperture of the size necessary to 105 record any particular impulse in a time equal to one-half the length of that impulse, so that under the present condition there is still sufficient of the impulse left to permit the diaphragms to open from zero to the 110 desired size. As they have already opened one-half of the necessary amount, however, it will be seen that unless their rapidity of opening is checked they will have opened 115 too far at the time the impulse ceases, thus producing too large an exposed area on the record film. I accordingly provide the means already described for dropping the apparatus to half speed, when the armature 120 191 engages the contact 193 and the impulse is still on the main line. This operation, it will be understood, occurs through the energizing of relay 197 which closes the armature 227 upon contact 228, thus closing the circuit through relay 237. As the circuit is closed between armature 231 and contact 230, owing to the action of cam 188, and also between armature 235 and contact 234, as the impulse is still on the main line and the primary circuit consequently closed, 125 130

the energizing of relay 237, as has been above described, closes the circuit through clutch magnets 77 which disconnects the full speed driving gear from the motor 69 and permits the half speed gear to come into operation. The rate of opening of the diaphragms is thus reduced one-half, and the remaining half of the impulse is just sufficient to permit them to complete the formation of the desired size of aperture. Just at or before the time at which the primary and secondary magnets reach their initial position, the cam 188 permits the contact 189 to open, thus breaking the clutch 70 operating circuit and permitting the apparatus to resume its normal speed. The dropping of the receiving apparatus to half speed, besides completing the record of the impulse being received, also gives the sending machine time to catch up with the receiving machine, so that the two are ready to start off with the next impulse more nearly in synchronism. The mode of operation above described permits my machine to 75 record properly a solid black such as is caused by the running together from the sending plate of several dots of maximum size. This occurs quite frequently unless special care is taken in making the plate to 80 avoid it. With my apparatus the main line simply remains energized, holding the shutter 115 raised and permitting a continuous exposure, or rather a series of maximum exposures, to be made.

85 The means above described thus serve, by delaying the operation of the receiving machine when it is faster than the sending machine, to prevent its acting out of step with the latter, so that each dot or impulse is 85 received and recorded by the receiving machine before the latter can pass into the condition for receiving a second dot or impulse. On the other hand, if the sending machine is operated at a higher speed than 90 the receiving machine, impulses can be received by the latter so long as they do not begin before the primary and secondary magnets start on their out-stroke. If the sending machine gets so far ahead of the 95 receiving machine that an impulse attempts to arrive before this time, the sending machine will immediately stop and wait for the receiving machine to catch up with it. This is done by means of the relay 148 which acts to break the main line, thus causing the sending machine to stop in the manner already described. The circuit of relay 148 and manner of closing the same have also been described, this action being controlled by the cam 179 which acts to close the contact 180 during the back stroke of the primary and secondary magnets.

95 My apparatus thus acts to transmit each dot or impulse as an individual operation, 100 the sending and receiving machines control-

ling each other at such intervals—at every impulse if necessary—as to maintain their relative conditions for sending and receiving dots within the required limits. It will thus be seen that neither synchronism nor a 70 uniform speed for either my sending or receiving machine is necessary, but that each dot or impulse is automatically sent and completely and perfectly recorded in its proper relation to the other dots or impulses. 75

Considering now the operation upon a brush reaching the end of a row of dots on the sending plate: If the apparatus is adjusted so that the sending and receiving machines operate in synchronism, and also if the distance between the successive brushes 19 is such that the second brush 19 is in a position to make contact with the first dot in the second row of dots immediately after 80 the first brush leaves the last dot in the first row, the operation of the apparatus will continue without interruption as if the dots were all in a continuous long row. This condition of affairs may, however, sometimes 85 be difficult to obtain in actual practice, and I therefore prefer to proceed in the following manner when the end of the row is reached: In the first place, I enlarge the distance between the successive brushes 19 so 90 that the first brush 19 will have passed over a space equal to one or more dots before the second brush is ready to contact with the first dot on the second row. During this 95 space, of course, no impulses pass over the 100 main line. I mount upon some moving portion of the receiving apparatus, preferably upon the hub of gear 90, a knife contact 266 so disposed that a short time before the end of the row is reached, preferably about one 105 dot before, this contact, which of course with the gear 90 and the shaft 91 makes one revolution for every revolution of the film carrying drum, will engage with a pair of contact springs 267, thus closing the circuit 110 through wire 268, magnet 269 and wire 270, the magnet 269 acting to throw the double switch 263, which comprises the armature 271 of the magnet 269, the armature 272 of the magnet 273 and the connecting bar 262 115 of insulating material, this bar carrying the three contact blocks, one, the block 261, already described, to which wire 260 is connected and with which brush 264 makes contact, and the contact blocks 274 and 275. It 120 will be seen that the throwing over of this double switch brings the block 275, which is permanently connected to the wire 276, under the brush 277, which is connected with the wire 278. The wire 278 has branches 125 279 and 280 leading, respectively, to relays 281 and 282, from the former of which a wire 283 leads to a point 284, from which it branches, one branch 285 going through the armature 286 of the relay 281, this armature 130

being adapted to be drawn by the relay, when energized, into contact with the contact 287, which is connected by wire 288 with armature 289 of relay 290, which armature is normally in contact with the back contact 291; wire 292 leads from the latter to the main line breaking relay 144 from which a wire 293 leads to battery 294, from which the wire 276, mentioned above as being connected with contact block 275, starts. From the point 284 the second branch 295 of wire 283, above-mentioned, leads to the contact 296 of the delayed circuit closer shown in Fig. 19. This circuit closer comprises the magnet 297 having the armature 298 in which is a guide-groove 299. In the guide-groove slides longitudinally a bar 300 which has at its outer end the contact 301 and which carries a toothed block 302. The bar 300 is adapted to be normally telescoped with the armature by means of the contractile spring 303 which is secured to the block 302 and to some fixed part of the armature. The delayed circuit closer is also provided with a shaft 304 which carries a screw 305 at its outer end, the shaft 304 being continuously rotated in any suitable manner, as by means of a gear 306 meshing with a pinion on shaft 126. The magnet 297 is connected by a wire 307 to the back contact 308 of relay 282, the armature 309 of which is connected by a wire 310 to the back contact 311 of relay 158; armature 312 of the latter relay is connected by a wire 313 to battery 314 from which wire 315 leads to the magnet 297. The contact 301 on the end of the telescopic bar 300 is electrically connected, preferably through the armature 298, to the wire 316 which connects with the battery 317, from which wire 318 leads to relay 282. From the latter, wire 280 leads to the junction of wires 279 and 278, as already described.

The operation of this delayed circuit closer is as follows: Assuming first, for the moment, that the end of the row has not been approached and that the double switch is in its normal position, as shown in the drawings, it will be seen that whenever the main circuit, and consequently the primary circuit, is broken, relay 158 will be deenergized and the circuit will be closed through armature 312, back contact 311, wire 310, armature 309, back contact 308, wire 307, magnet 297, wire 315, battery 314 and wire 313. This will energize the magnet 297, causing it to draw down its armature 298, which will bring the teeth on block 302 into engagement with the thread on screw 305. As this screw is constantly rotating it will cause the block 302, acting as a nut, to travel longitudinally thereon, thus drawing the bar 300 outwardly against the tension of the spring 303 until the contact 301 touches the contact 296. At that moment a circuit will be closed through 296, wire 295, wire 283, relay 281, wire 279, wire 280, relay 282, wire 318, battery 317, wire 316 and armature 298. Relay 282 will thus become energized, drawing armature 309 out of contact with back contact 308, thereby breaking the circuit through magnet 297 and permitting armature 298 to fly up, which will release the teeth on block 302 from engagement with the thread of screw 305 and will permit spring 303 to draw the bar 300 and block 302 back to normal position. Ordinarily, during the normal operation of the device, the primary circuit will be closed at frequent intervals, thus breaking the circuit of magnet 297 between armature 312 and back contact 311. If this occurs frequently enough contact 301 will never be carried far enough to engage contact 296. No harm is done, however, if it does engage contact 296, as the circuit will then be broken by relay 282, as above described. It will thus be seen that the delayed circuit closer has no function during the normal operation of the machine, that is, when the double switch 263 is in its normal position, which is the position shown in the drawings. When, however, the end of the row is approached, and the knife 266 closes the circuit between the springs 267, causing the magnet 269 to draw the double switch 263 into its second position, it will be seen that brush 277 engages block 275, as above set forth, and wires 278 and 276 are connected. A circuit now extends from contact 301 through armature 298, wire 316, battery 317, wire 318, relay 282, wire 280, wire 278, brush 277, block 275, wire 276, battery 294, wire 293, relay 144, wire 292, back contact 291, armature 289, wire 288, contact 287, armature 286, wire 285 and wire 295 to contact 296, this circuit being, however, broken between 287 and 286, and 301 and 296. The brush 19 continues to sweep over the few remaining dots on the line, each time making and breaking the main circuit and the primary circuit which passes through relay 158. This relay acts, therefore, to break the circuit through magnet 297 at frequent intervals by drawing down armature 312. Contact 301 is thus unable to reach contact 296 until the brush 19 has left the last dot in the row. Relay 158 then ceases to operate and the circuit through magnet 297 remains closed until contact 301 engages contact 296, thus closing the circuit through relay 282 which again breaks the circuit through magnet 297. In the short space of time, however, during which the circuit through relay 282 is closed, a circuit is also closed through relay 281 which causes armature 286 to be drawn over into contact with contact 287. A circuit is thus established through relay 144, as above described, this circuit including relay 281, so that the latter is maintained

closed and the circuit through it and through relay 144 is not affected by the breaking of the circuit between contact 296 and contact 301. This mechanism is for the time being 5 cut out and becomes inoperative so far as the circuit through the relays 281 and 144 is concerned. The effect of closing the circuit through relay 144 is to energize the latter and draw its armature 145 away from 10 its back-contact 143, thus breaking the main line. The main line being broken at the receiving end of the machine, when the second brush 19 comes in contact with the first dot 319 of the second row, it will close the circuit through binding post 50, wire 49, battery 55, wire 54, relay 53, wire 52, relay 51, and wire 47. This will cause armature 66 15 to engage the contact of relay 53 and armature 62 being against back contact 68 of relay 60 a circuit will be closed through armature 66, wire 65, battery 64, wire 63, magnet 40, wire 61, armature 62, back contact 68 and wire 67. The magnet 40 will thus be 20 energized, drawing out the clutch member 31 and stopping the sending machine. The armature 58 is held closed by the relay 51, as the circuit of the latter is closed owing to the brush 19 being in contact with the first dot 319, but the relay 60 will be deenergized, 25 thus permitting the armature 62 to engage the back contact 68, leaving the machine stationary, as long as the circuit through relay 60, which is the main circuit, remains broken. The sending machine will thus 30 remain stationary with the brush at the edge of the first dot of the second row and ready to be immediately started upon the closing of the main circuit at the receiving end, until the latter event takes place. This is 35 accomplished as follows: The shaft 91, continuing its rotation, carries the knife 266 out of contact with the springs 267, thus breaking the circuit through magnet 269. The double switch 263, however, retains its second 40 position until it is drawn back to its normal position by the operation of magnet 273. This occurs when the knife 266 engages a second set of contact springs 320, thus closing a circuit through wire 321, relay 290, wire 322, block 274, brush 323, wire 324, relay 325, wire 326, battery 327, wire 328, relay 329 and wire 330. The closing of 45 this circuit energizes relay 325 and also relay 290, the latter drawing armature 289 away from back contact 291, thus breaking the circuit through relay 281 and relay 144. The energizing of relay 329 draws its armature 331 away from its back contact 332, thus breaking the circuit of motor 69. The 50 latter circuit comprises, as will be seen, wire 333, motor 69, wire 334, storage battery 335, or other suitable source of power, and wire 336. The breaking of the driving motor circuit stops the receiving apparatus with the 55 knife 266 still in contact with the springs 320. The deenergizing of relay 144, as above described, permits armature 145 to contact with back contact 143, thus closing the main circuit. It will be seen that the main circuit cannot be broken at this time through the 60 action of relay 148 as the double switch, being in its second position, the circuit through the relay 148 is broken between brush 264 and block 261. The main line now being closed the sending machine resumes its operation and the primary circuit of the receiving machine is closed, thus energizing the relay 154. At the same time, relay 325 being energized, a circuit will be closed 65 through armature 337 of relay 154, wire 338, armature 339 and contact 340 of relay 325, wire 341, magnet 273, wire 342, battery 343 and wire 344. The closing of this circuit energizes magnet 273 and brings the double switch 263 back to its normal position. The 70 bringing of the double switch 263 back to its normal position breaks the circuit through relay 329 between block 274 and brush 323, thus releasing armature 331, permitting the circuit through motor 69 to close, and causing 75 the receiving machine to start. The sending and receiving machines now resume their normal operation of transmitting and recording the impulses, it being seen that by means of the mechanism above described 80 they must start simultaneously at the beginning of each row of dots.

Figs. 16 and 17 illustrate a modified form of aperture forming device which may be substituted for that shown in Figs. 14, 15 85 and 18. In this modification a pair of diaphragms 380 and 381 are used, provided, respectively with slots 382 and 383 extending approximately through semi-circumference and gradually broadening from points of 90 minimum width at one end to a considerable width at the other. The diaphragms are mounted upon shafts 384 and 385, by which they are rotated, the shafts preferably having 95 their axes located in a plane disposed at 45 degrees to the horizontal in order that the portions of the slot walls forming the light aperture 386 will give the latter the desired outline. One of the walls 387 of the slot 382 is preferably formed concentrically 100 with the axis of rotation of the disk, the other wall 388 of this slot having a gradually shortening radius, being preferably formed as an Archimedean spiral curve. The walls of the slot 383 in the other dia- 105 phragm are preferably offset equally from a curve concentric with the axis of that dia- 110 phragm. Fig. 17 shows the diaphragms 380 and 381 mounted in diaphragm box 387 through an aperture in the outer wall of 115 which comes the light from any suitable source 388. A screen 389 of ground glass 120 or the like is preferably used to prevent 125

the diffusion of the light passing through the diaphragms. A lens 390 may be used to focus the light upon the film carried by the drum 93. The diaphragms 380 and 381 are rotated constantly in opposite directions as indicated by the arrows, a light aperture 386 being formed where the slots 382 and 383 register. As will be apparent, this aperture, while maintaining a uniformly rectangular configuration, grows from a very small area when the narrow parts of the slots register to a much larger area when the broad ends of the slots are opposite each other. Further rotation of the diaphragms 15 will cause the slots to move out of register and for the half revolution corresponding to the outstroke of the primary and secondary magnets above described the aperture will be entirely closed. Owing to the 20 fact that the outer wall of slot 382 is concentric while the inner wall is an Archimedean spiral curve, the aperture 386 will increase in size while moving upwardly sufficiently to compensate for the rotation of 25 the drum 93. A drop shutter similar to that shown in Fig. 6, or other suitable means, are used for controlling the passage of light through the aperture, the operation being the same as with the aperture forming device shown in Fig. 18.

In Figs. 24 to 28, inclusive, I have illustrated a modification of my receiving apparatus by means of which I produce a picture record made up entirely of areas of 35 uniform size, arranged in juxtaposition and variously shaded from white through light and dark grays to black, or as nearly thereto as may be found desirable, thus producing a picture composed of shades or tones similar 40 to an ordinary photograph. The distinction between this type of record and that made by the apparatus above described, it will be understood, is that the latter is, like a halftone plate, composed entirely of areas of 45 solid black, the tones of the picture depending upon the sizes of these areas.

For forming this modified form of record the apparatus used is in the main the same as that above described. I substitute, however, 50 for the box 113 with its contained diaphragms and drop shutter, a box 400, in which are mounted a shaft 401 driven through suitable gearing from the main driving shaft of the receiving apparatus, 55 and a pair of shafts 402 and 403 driven from the shaft 401 by gearing 404. A diaphragm 405 is fixed to the shaft 402, this diaphragm, as shown in Fig. 24, being provided with a window or screen 406 of any suitable material shaded from substantial transparency at one end to, or nearly to, opacity at the other. This window may be prepared in a variety of ways, as, for instance, by making it of glass or mica, suitably smoked or tint-

ed, or by forming it of a piece of photographic film or plate which has been unevenly exposed to the action of light. The movements of the diaphragms 405 correspond with the movements of the aperture-forming diaphragms shown in Fig. 18, the 65 most opaque portion of the window being interposed between the source of light and the recording film at the beginning of the recording operation and corresponding with the minimum aperture formed by the diaphragms shown in Fig. 18. The diaphragm 405 turning continuously, window portions of successively increasing transparency are interposed in the path of the light so that the longer the making of an exposure is delayed by the action of the drop shutter, the less will be the obstruction to the light passing to the record film and the more intense will be the exposure of the latter. The drop shutter shown in this modification of my apparatus comprises the shutter proper 407 provided with the light aperture or slit 408 and mounted upon the free end of the armature 409 of the electro-magnet 410, corresponding to the shutter magnet 118, already 70 described. The electrical connections of this magnet 410 are exactly the same as those of the magnet 118 and are not therefore further described. The armature 409 is pivoted at 75 411 to the diaphragm box and is provided with a spring 412 to assist the action of gravity in drawing the armature away from the magnet and insure a rapid action 80 of the shutter. The shutter is raised or set at stated intervals by the cam 413 mounted 85 upon the projecting end of shaft 403, this cam corresponding in structure and operation to the cam 120 above described. The aperture 408 may be of such a size that when 90 the armature and shutter are lifted by the cam 443, the light aperture in the wall of the diaphragm box is exposed and so remains until the shutter drops, in which case an exposure will begin as soon as the dark portion 95 of the window 406 reaches the line of the light rays. In this case the exposure of the record film will vary both in length, dependent upon the time the shutter is open, and in intensity, owing to the movement of the diaphragm 405. I usually prefer, however, to rely entirely upon the latter mode of light control and accordingly make the aperture 408 narrow, so that when the shutter is raised by the cam the aperture in the 100 box wall is closed by the part of the shutter 105 below the aperture. In this case no exposure of the record film is made until the shutter drops, the exposure being practically instantaneous. The intensity of the exposure of the record film is dependent entirely upon 110 the portion of the window 406 interposed 115 in the path of the light rays at the instant of the release of the shutter. A shutter of 120 125

this nature is equally applicable for use with the aperture-forming diaphragms of the forms shown in Figs. 16 and 18.

In order to confine the exposure corresponding to each impulse to its proper position upon the record film, and to locate the several exposed areas upon the film in juxtaposition, I mount upon the shafts 402 and 403 a pair of diaphragms 414 and 415 of the form shown in Fig. 28. These diaphragms are of opaque material and are provided with slots 416 of substantially uniform width throughout. The edges of these slots are not concentric with the centers of rotation of the diaphragms, but are preferably formed of Archimedean spiral curves. At the point where these slots 416 coincide a light opening or aperture 417 is formed, which, while of constant area, moves during the rotation of the disks, for a slight distance across the line of the light beam coming through the aperture 418 in the box wall. The light beam, after passing through the aperture 417, passes through the window 406, which is made of sufficient width to intercept the light beam in whatever position it is thrown by the aperture 417. The modified beam then passes through a lens 419, which focuses it upon the sensitized recording surface 94. The diaphragms 414 and 415 being geared to maintain a constant relation with the drum 93 carrying the record film, place the exposure for each operation of the drop shutter in a definite position upon the film, although the latter is constantly moving. As pointed out, the edges of the slots 416 which together form the aperture 417 are not concentric with the axes of rotation of the diaphragms but are of a constantly increasing radius, so that it will be seen that the aperture 417 will constantly recede from these axes of rotation owing to the increase in length of the radii of curvature of the slot edges, thus, in effect, moving this aperture 417 upward. The relative rates of rotation of the diaphragms and of the drum 93 and the curvature of the spiral slot edges are so proportioned that the upward movement of the aperture 417 corresponds exactly with the movement of the portion of the film 94 on the drum 93 to be exposed. Thus, at whatever time during a particular cycle of my apparatus the exposure is made, only the desired predetermined film portion will be affected. As will be apparent, after the disks have rotated until the slots 416 are out of register no exposure is possible, and a second exposure cannot take place until the portions of the slots of least radius come into register. This will result in the exposure of another rectangular area of film directly adjacent to that previously exposed, so that the film will eventually be entirely covered with a series 60 of individual exposures of similar configura-

tion and area, but of varying degrees of light and shade.

Having thus described my invention, I claim:

1. The method of transmitting pictures, 70 consisting in preparing a transmitting record having its surface divided into a plurality of portions having areas proportional to the tones of corresponding portions of the picture, transmitting successive impulses each of a duration proportional to a dimension of one of said portions, utilizing said impulses to determine characteristics of successive portions of a record, the characteristics of said portions being proportional 75 to the first powers of the areas of corresponding transmitting portions.

2. The method of transmitting pictures by electricity, consisting in preparing a transmitting surface having areas of conductivity of dimensions proportional to the tones of corresponding portions of the picture, transmitting electrical impulses of durations proportional to the lengths of corresponding areas of conductivity, and utilizing 80 said impulses to expose successive portions of a photo-sensitive surface to quantities of light proportional to the squares of the durations of the impulses.

3. The method of reproducing pictures at 95 a distance, consisting in transmitting a series of impulses of durations corresponding to the tones of a picture, and recording said impulses in the form of dots on a recording medium, the duration of an impulse 100 determining more than one dimension of its dot.

4. The method of reproducing a half tone picture electrically, consisting in transmitting a series of impulses each proportional 105 to the square root of a unit tonal area of said picture, and reproducing by said impulses a series of tonal areas each directly proportional to the square of said impulse.

5. In the art of picture telegraphy, the 110 method of transmitting and reproducing pictures consisting in producing from the picture to be transmitted a surface, each superficial unit of which presents an electrical contact ranging from zero to maximum in direct proportion to the presence or absence of light in the corresponding unit area of the original picture; causing a current to pass from said surface and conducting such electrical current to a receiving 115 mechanism and there translating such received impulse into a projected beam of light proportioned as to quantity or duration in accordance with the character of the particular unit of the transmitting surface 120 being sent; and independently moving a receiving and recording medium across the path of said beam, but in timed relation to the varying quantity of duration thereof, whereby the surface of such medium is suc- 130

cessively exposed in light-sensitive units patterned in duplication of those of the original picture, and controlling the travel of said contact across the transmitting surface by the completion of the act of receiving and recording the preceding unit of light; thus governing the rate of origination of the succeeding electrical impulses by the rate of recording of the translated impulse immediately preceding each.

6. In a sending machine for picture transmission apparatus, in combination, a transmitting record having a surface, portions of which are capable of conducting electricity, and means for making contact with said conducting portions, said means comprising pulleys adapted to be moved axially from one side of said plate to the other side thereof, and an endless belt carried by said pulleys, said belt carrying a contact brush.

7. In a sending device for picture transmission apparatus, in combination, a record plate having a surface, portions of which are capable of conducting electricity, a pair of parallel shafts arranged one at each side of said record plate, a pulley carried on each of said shafts, means for moving said pulleys axially and at equal speeds along said shafts, means for rotating said pulleys, and an endless metallic belt carried by said pulleys and provided with a plurality of spaced contact brushes adapted to sweep over said plate.

8. In a sending device for picture transmission apparatus, in combination, a base, four parallel shafts mounted thereon, the two outer of said shafts being provided with screw threads, nuts mounted thereon, a frame connecting said nuts, a pair of pulleys mounted upon the inner pair of said shafts and within said frame, means for causing said pulleys to turn with the inner pair of said shafts while permitting axial movement of said pulleys with relation to said shafts, an endless belt provided with a contact brush carried by said pulleys, and means for rotating said shafts.

9. In picture transmitting apparatus, a sending device comprising a base, a support movably mounted thereon, a screw carried by said base for moving said support in one direction, a spring tending to move said support in the opposite direction, a sending record plate carried by said support, a contact member supported by said base, and means for causing said contact member to sweep over said plate.

10. In a sending device for picture transmission apparatus, a record plate having a surface comprising separated conducting portions, a contact brush adapted to sweep over said plate, driving means for causing relative movement between said plate and said brush, and means for rendering said driving means inoperative, said means being

incapable of operation except when said brush is in contact with a conducting portion of said plate surface.

11. In picture transmitting apparatus, a sending machine, a receiving machine, a main circuit connecting said machines, said sending machine comprising a record plate bearing a record of the picture to be sent, a contact brush adapted to sweep over said record plate and intermittently to close an electric circuit, driving means acting to cause relative movement between said brush and said record plate, an electro-magnet for rendering said driving means inoperative, an electric circuit passing through said electro-magnet, a relay acting when energized to close the main circuit at the sending machine and a second relay acting when energized to close the circuit through the said electromagnet, the field magnets of both these relays being in the circuit closed by said contact brush, and a third relay having its field in the main circuit and its armature and back contact in the circuit of said electromagnet, whereby said magnet circuit is closed only when said first two relays are energized and when said main circuit is broken at a point other than at the first named relay.

12. In picture transmission apparatus, a sending machine acting to send successive electrical impulses corresponding to successive portions of a picture, and a receiving machine adapted to record said successive impulses, and means controlled from the receiving end for preventing the sending of an impulse until the impulse previously sent has been recorded.

13. In mechanism for reproducing pictures telegraphically, a sending device acting to send a series of impulses corresponding to successive portions of a picture, a receiving device acting to record said impulses, means for driving said receiving device, and means for delaying said receiving device to permit it to record an impulse arriving after the normal interval.

14. In mechanism for reproducing pictures telegraphically, a sending device acting to send a series of impulses corresponding to successive portions of a picture, a receiving device acting to record said impulses, means for driving said receiving device, means for stopping said sending device to prevent the sending of an impulse until said receiving device is in a condition to receive said impulse, and means for delaying said receiving device to permit it to record an impulse arriving after the normal interval.

15. In telegraphy, a sending apparatus, a receiving apparatus including means for recording signals transmitted by the sending apparatus, means for preventing the sending of a signal by the sending apparatus when the receiving apparatus is not in a con-

- dition to record a signal, and means for delaying the operation of the receiving apparatus in order to allow it to receive and record a delayed signal.
- 5 16. In telegraphy, a sending apparatus, a receiving apparatus comprising a recording surface, means for making a record thereon, means for causing relative movement between said surface and recording means to 70
10 present a definite portion of the recording surface for receiving a record of each succeeding impulse, and means controlled from the receiving end to prevent the sending of an impulse until such definite portion of recording surface has been presented.
- 15 17. In apparatus for transmitting and recording electrical impulses, a sending device, power means for driving the same, a receiving device, power means for driving the receiving device, said sending device acting to 75
20 transmit a series of electrical impulses to said receiving device, said receiving device acting to record the impulses received from said sending device, and means controlled 80
25 from the receiving end for preventing the transmitting of a second impulse by said sending device until the previous impulse has been recorded by said recording device.
- 30 18. In mechanism for reproducing half-tone pictures electrically, a sending apparatus comprising means for transmitting a series of impulses corresponding in length to the sizes of successive half-tone dots, a receiving apparatus including means controlled by the received impulses for reproducing and recording half-tone dots corresponding to the half-tone dots of the transmitted picture, and means operating irrespective of the synchronism of the sending 85
35 and receiving apparatus for establishing the location of said reproduced half-tone dots with their centers equally spaced.
- 40 19. In an apparatus for transmitting half-tone pictures by electricity, a sending apparatus comprising a local circuit, means for closing the same for intervals corresponding to the sizes of the dots composing a half-tone, a device for driving said means, two relays having their magnets in said local circuit, an electrically operated device for discontinuing the action of the means for closing the first local circuit, a second local circuit including said electrically operated device, and closed by one of said relays, a receiving device, an impulse transmitting circuit acting to transmit impulses to said receiving device, said circuit being closed at the sending apparatus by the second relay in the said first local circuit, a 90
45 circuit breaking device controlled by said impulse-transmitting circuit acting to break said second local circuit when said impulse-transmitting circuit is closed, said receiving apparatus comprising means controlled by the closure of said impulse-transmitting circuit for recording the impulse transmitted, and means for breaking said impulse-transmitting circuit until said recording device is in condition to record an impulse to be transmitted.
- 50 20. In apparatus for reproducing half-tone pictures, a sending apparatus comprising a local circuit, means for closing said local circuit for intervals proportional to the sizes of the dots forming the half-tone picture to be transmitted, two relays having their magnets connected in series in said first local circuit, a second local circuit a power device for driving the means for closing the first local circuit, electrically operated means in said second local circuit acting when said circuit is closed to disconnect said power device, said second local circuit passing through the contacts of one of said relays in said first local circuit in such manner as to be closed by the energizing of the magnet of said relay, said second local circuit passing through the contacts of a third relay in such manner that said circuit is closed when said relay is deenergized, a receiving device, a main circuit connecting said sending and receiving devices, said main circuit at the sending device passing through the contacts of the second relay in said first local circuit in such manner as to be closed when said relay is energized, and through the magnet of said third relay, said main circuit at the receiving apparatus passing through the magnet of a relay forming a part of said receiving apparatus, and through the contacts of two other relays in such manner that when said relays are energized said main circuit will be broken, a local receiving circuit passing through the contacts of said first relay at the receiving apparatus in such manner as to be closed by the energizing of said relay, a recording apparatus controlled by the closure of said local receiving circuit, and means acting to energize one of said second and third receiving relays at such times as said receiving apparatus is not in a condition to record impulses.
- 55 21. In telegraphy, means for sending impulses, recording mechanism becoming sensitive after the passage of equal portions of the recording surface, and means controlled by the impulses for determining the time of making a record upon the recording surface.
- 60 22. In picture transmission mechanism, a sending machine acting to send a plurality of impulses corresponding to successive portions of the picture, the durations of said impulses corresponding to the tones of their respective picture portions, and a receiving machine adapted to record said impulses, said receiving machine starting the records of successive impulses at equally spaced area centers.

23. In telegraphy, means for sending impulses and receiving mechanism comprising a recording means and a recording medium for recording the impulses, becoming operative after a pre-determined relative movement between the recording means and the recording medium, said movement being determined independently of the initiation of the impulse.
- 5 24. In telegraphy, means for sending impulses, recording mechanism becoming operative after the passage of equal portions of the recording medium for recording the impulses, and movable means controlled by the impulses, the operation of the recording mechanism being determined by the amount of movement of the impulse controlled means.
- 10 25. In a telegraphic receiving apparatus, a movable member, means controlled by an impulse to be received for moving said member to a position determined by the length of said impulse, and means controlled by the movement of said member for making a record of said impulse, the operation of said first-named means and said record-making means being a synchronous.
- 15 26. In telegraphic recording apparatus, means for making a record, means actuated by the breaking of the impulse to be recorded for determining a characteristic of said record, a member movable to a position determined by the impulse to be recorded, and auxiliary means whose action is dependent upon the position to which said movable member is moved, acting, under stated conditions, to control the operation of the characteristic determining means.
- 20 27. In telegraphic receiving apparatus, in combination, a movable member, means controlled by the impulse to be received for moving said member in one direction, means for returning said member to its original position, and means mechanically distinct from said movable member for recording the impulse during the return stroke of said member.
- 25 28. In telegraphic receiving apparatus, in combination, a movable member, means controlled by an electrical impulse to be received for moving said member in one direction, means for returning said member to its original position, and means for recording said impulse, said recording means becoming sensitive at the beginning of the return stroke of said member.
- 30 29. In telegraphic receiving apparatus, in combination, a movable member, means controlled by an impulse to be received for moving said member from its initial position, means for returning said member to its initial position, and means for making a record of the received impulse, said recording means becoming sensitive at the beginning of the return movement of said movable member, a characteristic of said record being determined by the position of said movable member at the beginning of its return movement.
- 35 30. In telegraphic receiving apparatus, in combination, a movable member, means for moving said member at a pre-determined speed, means for returning said member to its initial position at twice the speed of its initial movement, and an impulse recording device controlled by said movable member but mechanically distinct therefrom.
- 40 31. In telegraphic receiving apparatus, in combination, a magnet, means for moving the same, an armature adapted to be attracted by said magnet when energized, and thereby moved therewith, the energizing of said magnet being controlled by the impulse to be received, and a device for recording said impulse, said recording device being controlled by the movement of said armature.
- 45 32. In telegraphic receiving apparatus, in combination, a plurality of magnets, means for moving them at different speeds, an armature adapted to be attracted by and to move with any of said magnets, and an impulse recording device controlled by said armature.
- 50 33. In telegraphic receiving apparatus, in combination, a pair of magnets, means for moving one of said magnets at a pre-determined speed, means for moving the other of said magnets at a higher speed, an armature adapted to be attracted by and to move with either of said magnets, and an impulse recording device controlled by said armature.
- 55 34. In telegraphic receiving apparatus, in combination, a primary magnet, means for reciprocating the same at a pre-determined speed, a secondary magnet, means for reciprocating the same at twice the speed of the primary magnet, an armature adapted to be attracted by and to move with either of said magnets, and an impulse recording device controlled by said armature.
- 60 35. In telegraphic receiving apparatus, in combination, a primary magnet, means for moving the same at a pre-determined speed, a secondary magnet, means for moving said secondary magnet, an armature adapted to be attracted by and to move with either of said magnets, said secondary magnet being active only to return said armature to its initial position, and an impulse recording device controlled by the movement of the armature.
- 65 36. In telegraphy, a receiving machine comprising means sensitive to a received impulse, recording means, and means for causing said recording means to be operated by said first-named means to make a record proportional to the duration of said impulse in a period less than the duration of the impulse.

37. In telegraphy, a receiving machine comprising means sensitive to a received impulse, recording means, and means for causing said recording means to be operated by 5 said first-named means to make a record proportional to the duration of said impulse in a period equal to one-half the duration of the impulse.
38. In telegraphy, an automatic sending 10 machine, and an automatic receiving machine acting to complete a record of transmitted impulses of varying lengths in a time interval equal to one-half of the duration of the respective impulses.
39. In telegraphy, a sending machine, an 15 automatic receiving machine acting to complete a record of an impulse sent in a time interval equal to one-half of the duration of the impulse, when said machines are operating synchronously, or said receiving machine is slower than said sending machine, and means for reducing the speed of the receiving machine one-half, during the recording 20 of an impulse, when said receiving machine is faster than said sending machine.
40. In telegraphy, a receiving apparatus 25 comprising a recording surface, means for making a record thereon, means for causing relative movement between said surface and recording means to present a fresh portion of the recording surface for receiving a record of each succeeding impulse, and means for actuating said recording means to complete a record of transmitted impulses 30 of varying lengths in a time interval equal to one-half of the duration of the respective impulses to be recorded.
41. In telegraphy, a receiving apparatus 35 comprising a recording surface, means for making a record thereon, means for causing relative movement between said surface and recording means to present a fresh portion of the recording surface for receiving a record of each succeeding impulse, means for actuating said recording means to complete a record of an impulse in a time interval equal to one-half of the duration of the impulse to be recorded, and means acting in case the record of an impulse is not completed in such 40 interval to reduce the speed of relative movement of the recording means and recording surface one-half.
42. In telegraphy, a receiving apparatus 45 comprising a recording surface, means for making a record thereon, said means including a power driven device acting to determine a characteristic of the record, means for causing relative movement between said surface and recording means to present a fresh portion of the recording surface for receiving the record of each succeeding impulse, and means for actuating said recording means to complete a record of an impulse in a time interval equal to one-half of the duration of the impulse to be recorded, and 50 means acting in case the record of an impulse is uncompleted in such interval to reduce the speed of relative movement of the recording means and recording surface and the speed of movement of the power driven device of the recording means one-half.
43. In telegraphy, a power driven sending 55 apparatus, a receiving apparatus comprising a recording surface, means for making a record thereon, means for causing relative movement between said surface and recording means to present a fresh portion of the recording surface for receiving a record of each succeeding impulse, and means for actuating said recording means to complete a record of an impulse in a time interval less than the duration of the impulse to be recorded, means acting in case the record of an impulse is not completed in such interval to reduce the speed of relative movement of the recording means and recording surface, and means to prevent the sending of an impulse until the record of the previous impulse has been completed. 60
44. In picture transmission mechanism, a 65 sending machine acting to send a series of impulses corresponding to the tones of successive parallel lines or bands composing a picture, a receiving device acting to receive and record said impulses in corresponding lines or bands, mechanism for synchronizing the machines at the beginning of each line, a line circuit connecting said machines, means for stopping the sending machine when said circuit is broken at the receiving machine, and means for breaking said circuit at the receiving machine, at the end of each line. 70
45. In picture transmission mechanism, a 75 sending machine acting to send a series of impulses corresponding to the tones of successive parallel lines or bands composing a picture, a receiving device acting to receive and record said impulses in corresponding lines or bands, mechanism for synchronizing the machines at the beginning of each line, a line circuit connecting said machines, means for stopping the sending machine when said circuit is broken at the receiving machine, means for breaking said circuit at the receiving machine at the end of each line, said means comprising an electro-magnet, acting, when energized, to break said circuit, a local circuit passing through said magnet, and a power-actuated device acting to close said local circuit at or near the end of each line, said power-actuated device acting, after a pre-determined interval to break said local circuit and to stop the operation of the receiving machine until the sending machine is in a condition to send the first 80 impulse of a new line. 85
46. In a telegraphic receiving apparatus, means for making a record, a device for determining a characteristic of said record, power-driven means for putting said device 90

in a condition for functioning, and means controlled by an impulse to be recorded for retaining said device in such condition.

47. In a telegraphic receiving apparatus, 5 a photo-sensitive surface, a shutter for controlling the access of light to said surface, means for setting said shutter at a definite phase in the operation of the apparatus but irrespective of the impulse to be recorded, 10 said means controlled by an impulse for governing the closing of said shutter.

48. In a telegraphic receiving apparatus, a light-sensitive surface, a shutter for controlling the access of light to said surface, 15 means acting positively to open said shutter at definite phases in the operation of the apparatus and to position the light-sensitive surface in timed relation with and to said shutter, and means for releasing said 20 shutter.

49. In a telegraphic receiving apparatus, a light-sensitive surface, a shutter for controlling the access of light to said surface, means acting positively to open said shutter 25 at definite phases in the operation of the apparatus and to position the light-sensitive surface in timed relation with and to said shutter, and means controlled by the received impulse for governing the inter- 30 val said shutter shall remain open.

50. In a telegraphic receiving apparatus, a photo-sensitive surface, a shutter for controlling the access of light to said surface, means for moving said photo-sensitive surface, and means for setting said shutter, said 35 two means being geared to maintain a constant relation, and means controlled by an impulse to be recorded for closing said shutter.

40 51. In mechanism for reproducing pictures, a sending apparatus comprising means for sending a series of impulses corresponding in lengths to the tones of the picture to be transmitted, and a receiving 45 apparatus comprising a shutter, means for setting the shutter at pre-determined intervals, and means controlled by said impulses for retaining said shutter in set position.

52. In picture reproducing mechanism, a 50 receiving apparatus comprising a drum, a sensitized film mounted thereon, and means for controlling the access of light to said sensitized film, said means comprising a device forming an aperture of constantly varying 55 area, and a shutter for controlling the passage of light through said aperture.

53. In mechanism for reproducing pictures, a sensitized surface, a device forming an aperture of constantly varying area 60 through which light may be admitted to said sensitized surface, a shutter for controlling the passage of light through said aperture, and driving means for moving said sensitized surface, operating the aperture-forming device and setting said shutter, said

mechanism acting to maintain a constant relation between the movement of said sensitized surface, aperture-forming device and shutter-setting mechanism, and means controlled by an impulse to be recorded for retaining said shutter in set position or releasing the same. 70

54. In a telegraphic receiving apparatus, a movable member, means for moving the same, a photo-sensitive surface, an aperture-forming device acting when operated to form an aperture of constantly changing area, a shutter for controlling the passage of light through said aperture to said photo-sensitive surface, means for setting said shutter, means controlled by said movable member for retaining said shutter in set position, means for moving said photo-sensitive surface, a source of power, and gearing for driving the means for moving said movable member, the means for moving said photo-sensitive surface, the aperture-forming device, and the shutter-setting means from said source of power, said gearing acting to maintain the relation between all of 80 said parts constant. 85

55. In telegraphy, a receiving apparatus comprising a photo-sensitive recording surface, means for making a record thereon comprising a power-driven aperture-forming device adapted to form an aperture of constantly varying area, and a shutter for controlling the passage of light through said aperture, means for causing relative movement between said surface and, recording means to present a fresh portion of the recording surface to the action of the light passing through the aperture formed by the movable aperture-forming device for every complete cycle of operation of said aperture-forming device, and means for actuating said shutter to cut off the passage of light through said aperture and determine the exposed area on said recording surface, at the completion of a time interval after the exposure of a fresh portion of recording surface proportional to the duration of the impulse to be recorded. 90 100 105

56. In telegraphy, a receiving apparatus comprising a photo-sensitive recording surface, means for making a record thereon comprising a power-driven aperture-forming device adapted to form an aperture of constantly varying area, and a shutter for controlling the passage of light through said aperture, means for causing relative movement between said surface and recording means to present a fresh portion of the recording surface to the action of the light passing through the aperture formed by the movable aperture-forming device for every complete cycle of operation of said aperture-forming device, and means for actuating said shutter to cut off the passage of light through said aperture and determine 110 115 120 125 130

- the exposed area on said recording surface, at the completion of a time interval after the commencement of the cycle of operation of the aperture-forming device equal to 5 one-half of the duration of the impulse to be recorded.
57. In telegraphy, a receiving apparatus comprising a photo-sensitive recording surface, means for making a record thereon 10 comprising a power-driven aperture-forming device adapted to form an aperture of constantly varying area, and a shutter for controlling the passage of light through said aperture, means for causing relative movement between said surface and recording means to present a fresh portion of the recording surface to the action of the light passing through the aperture formed by the movable aperture-forming device for every 15 complete cycle of operation of said aperture-forming device, means for actuating said shutter to cut off the passage of light through said aperture and determine the exposed area on said recording surface, at 20 the completion of a time interval after the commencement of the cycle of operation of the aperture-forming device equal to one-half of the duration of the impulse to be recorded, and means acting in case the record 25 of an impulse is not completed in such interval to reduce the speed of relative movement of the recording means and recording surface and the speed of movement of the aperture-forming device one-half.
- 30 58. In telegraphy, a receiving apparatus comprising a photo-sensitive recording surface, means for making a record thereon comprising an aperture-forming device acting automatically to form an aperture of 35 constantly varying area, and a shutter for controlling the passage of light through said aperture, power means for setting said shutter at intervals corresponding to the cycles 40 of movement of the aperture-forming device, an electro-magnet acting when energized to retain said shutter set and when de-energized to permit said shutter to close, means for causing relative movement between said surface and recording means to 45 present a fresh portion of the recording surface to the action of light for making the record of each succeeding impulse, and means for controlling the speed of relative movement of the recording surface and recording means and for controlling the operation 50 of said shutter, said controlling means including a fixed contact member, a movable contact member, primary means for moving said movable member out of engagement with said fixed contact member and returning it into engagement therewith, secondary 55 means for returning said movable member into engagement with said fixed member operating at twice the speed of said primary means, an electric circuit passing through 60 the shutter magnet, means for closing said circuit while an impulse is being received by the receiving apparatus, a second electric circuit passing through said shutter magnet, means for closing said second electric circuit while said movable member is out of engagement with said fixed contact member, and means for reducing the speed of relative movement of said recording surface and recording means and the speed of movement of said aperture-forming device one-half when said movable contact member is in engagement with said fixed contact member and said impulse-controlled circuit is closed. 65
59. In photo telegraphy, an aperture-forming device comprising a plurality of diaphragms grouped in such manner that portions of their edges form the sides of an aperture, the active portions of the edges of the rotatable diaphragms being formed to curves of progressively decreasing radii about the axes of rotation of the diaphragms, means for rotating the rotatable diaphragms to cause the same to form an aperture of variable area, and means for closing said aperture except while the same is increasing in area. 70
60. In photo telegraphy, an aperture-forming device comprising a fixed diaphragm and three rotatable diaphragms grouped in such manner that portions of their edges form the sides of an aperture, the active portions of the edges of the rotatable diaphragms being formed to curves of progressively decreasing radii about the axes of rotation of the diaphragms, means for rotating the rotatable diaphragms to cause the same to form an aperture of variable area, and means for closing said aperture except while the same is increasing in area. 75
61. In photo telegraphy, in a recording apparatus, a photo-sensitive surface, and means for controlling the access of light thereto, said means comprising a device acting to form an aperture of constantly varying area, a shutter, means for setting said shutter, and means for preventing the passage of light through said aperture except during the period extending from the time of setting of said shutter until the area of said aperture has reached a maximum. 80
62. In impulse recording apparatus, a translucent screen, means for illuminating an area of said screen proportional to an impulse to be recorded, and means for making a photographic record of said illuminated area. 85
63. In impulse recording apparatus, a translucent screen, means for illuminating a portion of said screen of an area proportional to the square of the duration of an impulse. 90

impulse to be recorded, and means for making a photographic record of said illuminated portion.

64. In a photographic recording apparatus, a photo-sensitive surface, a source of light, means forming an aperture through which the light passes from said source to said photo-sensitive surface, and a screen of translucent material interposed in the 10 path of the light passing to said surface.

65. In impulse recording apparatus, a recording surface, and means for producing a record of an impulse thereon of an area proportional to the square of the duration of 15 said impulse.

66. In a picture telegraph apparatus, means for generating and transmitting electrical impulses controlled by the successive tone values of a master record to be transmitted, means for receiving said transmitted impulses and for translating them successively into light rays, means for con-

trolling automatically the area and duration of the respective rays and means for projecting the successive rays upon a recording 25 medium, in correspondence with the successive tone values of the master record.

67. In a picture telegraph apparatus, the combination of means for automatically producing an interrupted light ray whose 30 continuity varies in accordance with the duration of flow of an electric current, said current flow indirectly creating said ray, means for recording the ray photographically, said recording means operating to 35 govern the means initiating the flow of said current and to prevent its flow until the recording means has completed the registration of the ray created by the current flow prior to interruption.
